SECTIONAL CAST METAL BOILER

Louis N. Hunter, Johnstown, Pa., assignor to
 National Radiator Corporation, Johnstown, Pa.,
 a corporation of Delaware

Application May 6, 1931, Serial No. 535,332

12 Claims. (Cl. 122—223)

This invention relates to water heaters and boilers, and more particularly to heaters of the type comprised of a plurality of cast metal sections and wherein the heater is especially adapted 5 to be fired by a gas burner.

Boilers of this type are generally formed of a plurality of parallel sections, each of which is hollow, to provide a water chamber within the sections, and the sections are in communication 10 with each other through nipples fitted into registering ports in the sections. The sections themselves are maintained in spaced relation to provide flues between the sections through which hot gases of combustion can circulate. 15 According to the present invention there is provided a furnace of improved construction wherein a more efficient circulation of water within the sections is set up and wherein a large surface area is provided for the absorption of heat 20 from the flue gases.

The invention may be readily understood by reference to the accompanying drawings in which Figure 1 represents a front elevation of a water heater or boiler constructed in accordance 25 with my invention;

Figure 2 is a side elevation thereof; Figure 3 is a detail view on a larger scale showing three sections arranged together, the view being in the same plane as Figure 1. In Figure 30 3 the hood is not shown;

Figure 4 is a transverse vertical section through one of the side sections of the boiler;

Figure 5 is a fragmentary view of the top of the boiler showing the hood in place thereon;

Figure 6 is an elevation of one of the sections, the view being in a plane at right angles to Figure 3;

Figure 7 is a transverse vertical section through the section shown in Figure 6, the view being in 40 substantially the plane of line VII—VII of Figure 6; and

Figure 8 is a side elevation of the section shown in Figure 7.

The water heater or boiler, as viewed in Figure 45 1, is comprised of two side sections 2 and 3 between which are a plurality of intermediate sections 4. All of the sections are made of cast iron. There may be any desired number of intermediate sections 4, this depending on the 50 capacity of the furnace. The construction of these intermediate sections is best seen by reference to Figures 6 and 7. As shown in Figures 6 and 7, each of these intermediate sections is hollow, the interior thereof being designated 5.

55 At the front and rear of the bottom portion of

each section are hub portions 6 having each an opening therein for the reception of a nipple, so that when two sections are placed together face-to-face the hub portions 6 will come together and the nipple serve to form a tight joint between 60 such adjacent sections. In the center of the top of each section 4 is a similar opening 7, so that all of the sections will communicate with each other at the top.

The lower portion of the section between the 65 front and rear hubs 6 is of downwardly decreasing cross-section, as shown in Figure 7, this tapered portion being designated 8. Cast integrally on this portion 8 are a plurality of vertically extending fins 9. These fins provide heat absorbing surfaces. Each side face of the section is transversely corrugated, the corrugations on one side face being designated 10 and on the other side face being designated 11. The corrugations 11 are staggered with reference to the corrugations 70 10, so that when two sections are jointed together, as shown in Figure 3, the gases which travel up between the vertically extending fins 9 will be delivered into the bottom of a sinuous passage 12 formed between the ribs or corrugations 10 of one 75 section and the ribs or corrugations 11 of the adjacent section, as will be clearly seen in Figure 3. The gas passages are of upwardly decreasing width and are free of pockets where dead gases 80 may accumulate so that the gases travel through the flues with sufficient velocity and effective heat transfer is obtained. This decrease in the width of the passages can be seen in Figure 3 and is obtained by decreasing the depth of the corrugations. 85

Above the corrugated portion of the section is a flat top portion 13, and the hub or boss 7 at the center of the top of the section is formed in this flat portion. The section is provided with marginal flanges 14, these flanges coming together in abutting relation to substantially close the space between the sections except, however, that the flanges are cut away at 15, as shown in Figure 3, to provide elongated vertical windows across the front of the furnace, the purpose of 90 these windows being to give access to the flue spaces between the sections. In the completed furnace cover plates are provided for these windows. The marginal flange is also broken away at the top of the section, as indicated at 16, so that 100 the gases of combustion, after traveling up the sinuous passages 12, flow between the flat surfaces 13 in an extension of the flue passage 12, and escape at the top of the boiler through the 105 passages provided at 16 where the marginal flanges 110

are cut away. The extension is designated 12^a in Figure 3.

In order to collect the gases which rise between the various sections, a hood 17 is set on the top 5 of the furnace, this hood being shown in Figures 1, 2 and 5.

Referring again to Figures 6 and 7, it will be seen that there are provided inside the section, in the chamber 5, two series of transverse plates or 10 baffles 18 and 19. The series of baffles 18 is located forwardly of the center line of the section and the baffles 19 are located rearwardly of the center line. The baffles 18 have a slight upward slope 15 from the boiler toward the center line of the section, and the baffles 19 are similarly sloped. The baffles 18 do not extend to the front wall of the boiler nor do they extend to the center line, but they span the greater portion of the distance 20 between the center line and the front. The baffles 19 are similarly arranged in the back half of the section. It will also be noted that the bottom 25 of the section is also sloped slightly from the front and rear bosses or hubs 6 upwardly toward the center.

25 The hottest part of the boiler is mid way between the front and the back walls thereof directly over the center of the burner. Consequently, the water is hottest at this point. By the arrangement of the internal baffles 18 and 19 as described, 30 there is a clear unobstructed vertical passage up the center of the section between the inner ends of the baffles 18 and 19. The coolest portions of the boiler are immediately adjacent the front and rear walls. The construction of the internal 35 baffles allows an unobstructed vertical passage between the outer ends of the baffle 18 and the front wall of the boiler, and likewise there is an unobstructed vertical passage between the outer ends of the baffle 19 and the rear wall of the section.

40 By means of this arrangement the highly heated water at the center of the section rises up the central passageway as indicated by the dotted arrows, flows laterally between the baffles 18 and 19 to the unobstructed vertical passageways at the 45 front and rear of the section, and having cooled in this travel drops down into the bottom part of the section where, as it becomes increasingly hot, it is forced toward the center and again repeats its cycle of circulation. The internal baffles thereby 50 provide the effect of a true tubular structure with divided circulation between both the front and the rear walls with the structural advantages, however, of an integral cast metal section. This tubular effect provided by the provision of the baffles 18 and 19 weighs less than a cast metal section 55 would weigh if made with true tubular passageways, as has heretofore been proposed.

The internal baffles 18 and 19 have the further effect of considerably strengthening the sections, 60 so that the corrugated walls of the sections can be relatively thin and light and still have ample strength.

65 It will be noted, moreover, that while the sections are corrugated, and the corrugations are staggered, so that when two sections are put together, a substantially sinuous passage 12 is provided between them, yet the corrugations 10 and 11 do not project beyond the plane of the marginal flanges of the section, or beyond the 70 plane of the hub or boss portions 6 and 7. This is clearly apparent from Figures 7 and 8 where it is readily seen that the outermost portions of the corrugations 10 and 11 do not extend out as far as the marginal portions of the sections. This 75 is of considerable advantage from a manufac-

ing standpoint, both for the reason of casting and also because of the fact that the section can be laid on a flat grinding surface and the faces of all of the flanges 14 and the hubs 6 and 7 smoothed off in a single operation.

80 Heretofore where corrugations have been provided it has been proposed to have these corrugations project beyond the plane of the surface of the section in order to produce an overlapping effect.

85 The side sections 2 and 3 are substantially similar to the intermediate sections except that the outer face thereof is smooth, but the internal baffles being provided. Each side section is provided with a downwardly projecting solid integral leg portion 20 so that the bottoms of the intermediate sections 4 are supported in a plane above the floor on which the boiler is set. This space under the intermediate sections provides the fire 90 box, and I have shown this fire box as being provided with a burner manifold 21 extending across the front of the furnace which supplies gas to a plurality of burners 22, the burners extending from the manifold to the rear of the furnace. The side sections, moreover, are provided on the 95 outer faces thereof with an inlet connection 23 which is at the center of the section near the bottom thereof and an outlet opening or connection 24 near the top thereof.

100 Each of the sections 4 has at the top thereof an upstanding flange 25 and outside of this flange is a shoulder or ledge 26. The side sections 3 and 4 have a similar flange 27 extending from the front to the rear thereof, this flange having an outer ledge 28. The purpose of these flanges and 105 ledges is to provide a means for holding the hood 17 in place on the top of the furnace. The hood sets outside the flanges 25 and 27, resting on the shoulders 26, and a furnace cement can be used to make the joint tight. The advantage of this 110 arrangement over constructions heretofore provided has been that as heretofore constructed the cement could break loose and fall down into the 115 passageways between the sections.

120 With the present construction the cement is outside the flanges 25 and 27 and if it comes loose it lodges on the outside of the furnace and cannot get down between the sections.

125 The boiler or heater as thus constructed provides a structure which is highly efficient. The sinuous flues 12 between the adjacent sections give a long gas travel, while the provision of the fins 9 below the corrugated portions increases the 130 heat-absorbing area of the section and serve to distribute the flue gases. The internal baffles as 135 arranged in each section produce, in effect, a number of horizontally extending passageways going to the front and the back of the section from the center thereof, allowing for the circulation of water in the manner described. This 140 gives the advantage of a section having individual flues the lightness of weight and a large heating surface of the continuous section. The provision of individual tubes, moreover, is not so desirable because the individual tubes form dead air pockets 145 through which the gases do not circulate efficiently.

145 While I have shown and described a preferred embodiment of my invention, it will be understood that this is merely by way of illustration and that various changes and modifications may be made in the detailed construction and arrangement of parts within the contemplation of my invention and under the scope of the following claims.

I claim:

1. In a heater of the class described, an integral cast metal section having spaced apart side walls and having a plurality of straight internal baffles connecting said side walls, the baffles being arranged in spaced apart vertical series with a common vertical channel between the series of baffles, said vertical channel leading from a common transverse bottom portion of the section below the baffles said transverse bottom portion being horizontal and extending across the full length of the section, the baffles being of such length as to extend from the central passage to a position near the ends of the sections; there being a single open passage at each end of the sections, these open passages leading from the said bottom portion up past said series of baffles, the baffles of each series having a slight upward inclination from their outer ends toward the center of the section, the single open passage along the bottom of the section having a greater cross-sectional area than the cross-sectional area of the passageways formed between the baffles. 80
2. In a heater of the class described, an integral cast metal section having continuous spaced apart side walls, two series of transverse baffles within the section connecting the side walls, one series being disposed at one side of the center line of the section and one series being disposed at the other side of the center line of the section, said baffles being sloped downwardly from the inner ends thereof toward the outer edges of the sections and being arranged to provide an unobstructed common vertical central channel between the two series of baffles, there being a circulating space across the full length of the top of the section above said series of baffles, and an unobstructed channel at the outer end of each series of baffles, the section having a transverse bottom portion below the baffles into which the central and side channels open, the bottom portion extending horizontally along the length of the section, the channels at the outer ends of each series of baffles being unobstructed between the ends of the baffles and the outside end walls of the section. 85
3. In a heater construction of the class described, an integral cast metal section having spaced apart continuous side walls, the lower portion of which is provided with a plurality of spaced apart vertically extending upwardly diverging fins and the intermediate portion of which is provided with transverse corrugations, the corrugations on one side being staggered with reference to those on the other, said sections having surfaces thereon adapted to abut against corresponding surfaces of an adjacent section, the peaks of the corrugations lying within the plane of such surfaces, the diverging fins aiding to provide a distribution of flue gases across the full depth of the section. 90
4. In a heater construction of the class described, an integral cast metal section having spaced apart continuous side walls, the lower portion of which is provided with a plurality of spaced apart vertically extending fins and the intermediate portion of which is provided with transverse external and internal corrugations, the corrugations on one face being staggered with reference to those on the other, said sections having surfaces thereon adapted to abut against corresponding surfaces of an adjacent section, and two series of transverse baffles within the section one at the front of the center line there- 95
- of, said baffles connecting the side walls of the section intermediate the corrugations, said baffles being arranged in two vertical series separated from each other by a common vertical passage and extending from the vertical passage in opposite directions toward the ends of the section, there being a vertical passage at each end of the section at the ends of the baffles, the section having a continuous horizontal bottom portion into which said vertical passages lead, said bottom portion being horizontal. 100
5. In a heater construction of the class described, a metal section having spaced apart side walls, the section having a lower portion, an intermediate portion and an upper portion, the lower portion of the section comprising a continuously open horizontal passage extending substantially the full length of the section, the intermediate portion of the section having a vertical series of internal baffles at each side of the center line of the section extending longitudinally of the section, there being a common vertical channel between the two series of baffles leading from the bottom portion of the section to the top portion of the section, said baffles being so disposed as to leave vertical passages at each end of the section leading from the top portion into the bottom portion, the bottom portion of the section having connector ports in the side faces thereof at each end thereof, the top portion of the section having a connector port in each side face thereof at the center, the interior of the section being such that circulation in a generally horizontal direction may take place at substantially any plane in the section across the entire width of the section. 105
6. In a heater construction of the class described, a metal section having spaced apart side walls, the section having a lower portion, an intermediate portion and an upper portion, the lower portion of the section comprising a continuously open horizontal passage extending substantially the full length of the section, the intermediate portion of the section having a vertical series of transversely extending internal baffles at each side of the center line of the section, there being a common vertical channel between the two series of baffles leading from the bottom portion of the section to the top portion of the section, said baffles being so disposed as to leave vertical passages at each end of the section leading from the top portion into the bottom portion, the bottom portion of the section having connector ports in the side faces thereof at each end thereof, the top portion of the section having a connector port in each side face thereof at the center, said section having an internal baffle in the top portion thereof above said central channel and below said port, the interior of the section being such that circulation in a generally horizontal direction may take place at substantially any plane in the section across the entire width of the section. 110
7. In a heater construction of the class described, a metal section having spaced apart side walls, the section having a lower portion, an intermediate portion and an upper portion, the lower portion of the section comprising a continuously open horizontal passage extending substantially the full length of the section, the intermediate portion of the section having a vertical series of internal baffles at each side of the center line of the section, there being a common vertical channel between the two series of baffles leading from the bottom portion of the section to the top portion of the section, said baffles being 115
- 120
- 125
- 130
- 135
- 140
- 145
- 150

so disposed as to leave vertical passages at each end of the section leading from the top portion into the bottom portion, the bottom portion of the section having connector ports in the side faces 5 thereof at each end thereof, the top portion of the section having a connector port in each side face thereof at the center, the side walls of the intermediate portion of the section having external and internal corrugations, the corrugations on 10 one side being staggered with respect to those on the other side, the baffles being positioned between the corrugations, the corrugations having a slight inclination upwardly from the ends toward the center of the section, the baffles being substantially 15 parallel with the corrugations.

8. In a heater construction of the class described, a metal section having spaced apart side walls, the section having a lower portion, an intermediate portion and an upper portion, the lower 20 portion of the section comprising a continuously open horizontal passage extending substantially the full length of the section, the intermediate portion of the section having a vertical series of internal baffles at each side of the center line of 25 the section, there being a common vertical channel between the two series of baffles leading from the bottom portion of the section to the top portion of the section, said baffles being so disposed as to leave vertical passages at each end of the 30 section leading from the top portion into the bottom portion, the bottom portion of the section having connector ports in the side faces thereof at each end thereof, the top portion of the section having a connector port in each side face thereof 35 at the center, the side walls of the intermediate portion of the section having external and internal corrugations, the corrugations on one side being staggered with respect to those on the other side, the baffles being positioned between the corrugations, the corrugations being of vertically 40 diminishing depths and having their outer surfaces in the same plane, whereby the width of the passage between the sections diminishes toward the top of the boiler when a plurality of said sections are arranged side-by-side in a vertical plane. 45

9. A gas fired boiler comprising a plurality of metal sections arranged in side-by-side relation, each section having a bottom portion, an intermediate portion and a top portion, gas circulating 50 passages being provided between the adjacent sections, intermediate portions of the sections having external and internal corrugations thereon, those on the one side of the section being staggered with reference to those on the other, 55 whereby the gas passage between the intermediate portions of the adjacent sections is sinuous, said gas passage being of upwardly decreasing width, the bottom portion of the section being downwardly tapered and having vertically extending upwardly diverging fins thereon for directing the gases into said gas circulating passages and distributing the gases across the depth 60 of the section.

10. In a heater of the class described, a sub-

stantially rectangular section having spaced apart side faces enclosing a substantially rectangular chamber, said chamber being provided with two series of longitudinally extending internal baffles one at each side of the vertical center line of the section, said baffles being of such length that there is a substantially unobstructed vertical channel between the two series at the center of the section and a substantially unobstructed vertical channel between the outer ends of the baffles and the outermost side edges of the section, all of said vertical channels opening into a common space in the upper part of the section, the section having a central port in a side face thereof within the confines of the section and above said series of baffles through which communication may be established with other sections, there being circulating spaces within the section above the series of baffles at each side of said port. 85

11. In a heater of the class described, a substantially rectangular section having spaced apart side faces enclosing a substantially rectangular chamber, said chamber being provided with two series of longitudinally extending internal baffles one at each side of the vertical center line of the section, said baffles being of such length that there is a substantially unobstructed vertical channel between the two series at the center of the section and a substantially unobstructed vertical channel between the outer ends of the baffles and the outermost side edges of the section, all of said vertical channels opening into a common space in the upper part of the section, the section having a central port in a side face thereof within the confines of the section and above said series of baffles through which communication may be established with other sections, there being circulating spaces within the section above the series of baffles at each side of said port. 90
